(57) **CLAIM**

The ornamental design for electronic refrigeration controller, substantially as shown.

DESCRIPTION

FIG. 1 is a front, top, right-hand side perspective view of an electronic refrigeration controller comprising a new, original and ornamental design;

FIG. 2 is a front view thereof;

FIG. 3 is a left-hand side view thereof;

FIG. 4 is a right-hand side view thereof;

FIG. 5 is a back view thereof;

FIG. 6 is a top view thereof; and,

FIG. 7 is a bottom view thereof.

The broken lines are included for the purpose of illustrating portions of the electronic refrigeration controller that form no part of the claimed design.
